FIG.2.

FIG. 3.

INVENTOR
Frederick Selwyn
John C. Bradley

UNITED STATES PATENT OFFICE.

FREDERICK GELSTHARP, OF TARENTUM, PENNSYLVANIA, ASSIGNOR TO PITTSBURGH PLATE GLASS COMPANY, A CORPORATION OF PENNSYLVANIA.

APPARATUS FOR APPLYING POLISHING MATERIAL.

Application filed June 6, 1921. Serial No. 475,503.

To all whom it may concern:

Be it known that I, FREDERICK GELSTHARP, a subject of the King of Great Britain, and a resident of Tarentum, in the county of Allegheny and State of Pennsylvania, have made a new and useful invention in Improvements in Apparatus for Applying Polishing Material, of which the following is a specification.

10 The invention relates to apparatus for applying polishing material such as rouge to a polishing machine. The machine illustrated is a plate glass polisher of the rotary type, but it will be understood that the invention is not limited to use with this particular machine which may vary widely in construction, and which for simplicity of illustration is shown in a somewhat diagrammatic form. The invention has for its 20 primary object the provision of an arrangement which will insure a uniform feed of material from a single source through a plurality of supply pipes leading to different parts of the polisher. Certain embodiments of the invention are illustrated in the accompanying drawings, wherein:

25 Figure 1 is a diagrammatic plan view showing a four runner plate glass polishing machine with the ends of four supply pipes leading thereto. Fig. 2 is a side elevation partially in section of the construction of Fig. 1 and the feed apparatus to which the invention particularly relates, and Fig. 3 is a perspective view showing a modified feed construction.

Referring to Figs. 1 and 2, 1 is a polishing table over which are mounted four runners, 2, 3, 4 and 5, each mounted to rotate about its axis and provided with a plurality of runner discs 6, having the usual facing of felt. The table is driven in a clockwise direction, as indicated by the arrow in Fig. 1, which causes a rotation in a similar direction of the four runners. A polishing 40 mixture of rouge and water is supplied to the table through the pipes 7, 8, 9 and 10, the said pipes delivering in front of the runners as indicated in Fig. 1 so that each runner has its own individual supply of polishing material.

The pipes are fed from the supply tank or hopper 11, as indicated in Fig. 2. The hopper 11 delivers to the distributor 12, mounted so as to pivot freely at 13 and

comprising a pair of triangular receptacles 55 14 and 15. The receptacles 14 and 15 are adapted to discharge into the hoppers 16 and 17, depending upon the position assumed by the distributor 12, suitable stops 12^a being provided to limit the tilting of the distributor. When the distributor is in the position indicated in Fig. 2 it discharges into the hopper 16, and at this time a mixture of the water and rouge is accumulating in the receptacle 15, such accumulation continuing until the weight of the mixture overbalances the distributor and causes it to tilt so as to discharge into the hopper 17, thus bringing the receptacle 14 into receiving position. This back and forth movement of the distributor will continue automatically, so that the supply of rouge and water is equally distributed between the two hoppers 16 and 17.

Beneath the hoppers 16 and 17 are other 75 distributors 18 and 19, each comprising a pair of triangular receptacles and corresponding in action with that heretofore described in connection with the distributors 12, the arrangement being such that the distributor 18 divides its material equally between the hoppers 20 and 21 and the distributor 19 divides its material equally between the hoppers 22 and 23. In this way the supply of material from the hopper 11 is 80 85 equally divided and distributed between the four hoppers 20, 21, 22 and 23 and the four supply pipes 7, 8, 9 and 10.

The above arrangement gives an even supply of polishing material to the runners 90 and to all parts of the table, such as would not be secured by the use of four pipes leading directly from the hopper 11, as the quantity of material fed is relatively small and the pipes must be made small, and as 95 a result they tend to clog, so that where a plurality of pipes are supplied simultaneously from the same source, the flow from the pipes soon becomes uneven. The arrangement also gives a better supply to all 100 parts of the table than is the case where all of the material is supplied through a single pipe, since in that case the distribution from the point of supply to the various portions of the table is not at all uniform, certain of the runners getting a relatively small supply of material as compared with others and certain parts of the table being exposed to

the action of less polishing material than others, all of which tends to produce uneven polishing.

The arrangement as shown is applied to four pipes, but it will be understood that this number may either be decreased or increased, depending upon requirements, and that the shape of the distributors may be modified to a considerable extent.

10. In the modification illustrated in Fig. 3, the distribution from the hopper 24 to the supply pipes 25, 26 and 27, etc., leading to the polishing machine is secured by means of a rotating spout 28. This spout is arranged 15 to discharge successively into the compartments 29, 30, 31 and 32 and is rotated by means of a belt 32 extending around the pulley 34 and around a corresponding pulley on the axle of one of the polishing runners.
20. The upper end of the spout 28 is provided with the funnel 35 for receiving the mixture of water and rouge from the spigot 36. This arrangement gives a distribution corresponding to that secured by the construction 25 of Fig. 2. In this construction or in that of Fig. 2, the four pipes may be made as large as desired so that there is no danger of clogging.

What I claim is:

30. 1. In combination with a polishing machine, a plurality of supply pipes leading to different parts of the machine, a source of supply of a mixture of water and polishing

material, an outlet from the source of supply, and automatic shifting means intermediate the outlet and said pipes whereby the flow from the outlet is divided and each pipe supplied intermittently with a predetermined proportion of the mixture.

2. In combination with a polishing machine, a plurality of supply pipes leading to different parts of the machine and each provided with a receiving receptacle, a source of supply of a mixture of water and polishing material having a discharge outlet, and automatic means intermediate the source of supply and said receptacles for dividing the discharge from the source of supply and intermittently supplying a portion of said discharge to each of said receiving receptacles.

3. In combination with a polishing machine, a plurality of supply pipes leading to different parts of the machine and each provided with a receiving receptacle, a source of supply of a mixture of water and polishing material, an outlet from the source of supply, and automatic means intermediate said outlet and the receptacles operated by the flow of the mixture for supplying said receptacles successively and intermittently from said discharge outlet.

In testimony whereof, I have hereunto subscribed my name this 18th day of May, 1921.

FREDERICK GELSTHARP.
